Application May 24, 1949, Serial No. 94,955

2 Claims. (Cl. 196—50)

1

The present invention relates to the conversion of hydrocarbons and, more particularly, to the conversion in liquid phase of mixtures of hydrocarbons having relatively low octane numbers to mixtures of hydrocarbon having relatively high octane numbers; the conversion being carried out in the presence of hydrogen fluoride and at elevated temperatures.

The treatment of mixtures of hydrocarbons with hydrogen fluoride probably was first disclosed by Hofman, et al. in British patents, Nos. 292,932 and 292,933. These investigators (Brit. 292,932) proposed to treat petroleum fractions boiling within the range of 122° to 437° F. with hydrogen fluoride at ambient temperature for 1 to 24 hours to remove olefinic bodies.

Frey in U. S. Patent No. 2,403,649, discloses that hydrocarbon material consisting predominantly of saturated hydrocarbons when subjected to the action of a substantial proportion, 0.2 to 4 times by weight, of concentrated hydrofluoric acid at a suitable reaction temperature and pressure undergoes several types of reactions.

Ridgway et al. in U. S. Patent No. 2,454,615, have disclosed that when gas oil, either virgin gas oil or recycle gas oil, is treated at elevated temperatures of 212° to 446° F. and preferably 284° to 349° F. for 2 to 4 hours, the gas oil is cracked to about 39 per cent gaseous products about 12 per cent gasoline (C₆—200° C.) and the balance about 49 per cent tar. These investigators also point out that, while the foregoing results are obtained when employing an oil to hydrogen fluoride ratio of 1 to 2.95 (by weight) the amount of tar produced is increased when the ratio is decreased. Thus, when the ratio of oil to hydrogen fluoride is 1 to 1.93 (by weight), the total gas produced is 31 per cent, the gasoline is about 16 per cent and the tar is about 53 per cent. It has now been discovered that several factors other than oil to acid ratio and reaction temperature affect the results produced when hydrocarbons are treated with hydrogen fluoride at elevated temperatures. For example, it has been discovered that when less than 3 parts by volume of acid is used per volume of oil to be treated improved results are obtained. This is in direct contradiction of the results obtained by Ridgway et al. In fact it has been found that best results are obtained when treating a naphtha by using an amount of hydrofluoric acid more than that required to saturate the hydrocarbon charge with hydrogen fluoride but not exceeding about 2 volumes of hydrofluoric acid per volume of charge stock.

2

It has also been discovered that a 75 per cent or better ultimate yield of liquid product having a 90 per cent point below the 10 per cent point of the charge stock can be obtained in a multi-pass operation when the conversion per pass is less than 40 per cent say of the order of 20 per cent to 30 per cent or less. Such conversions are obtained when the residence time is of the order of ten minutes or less, say 2 to 5 minutes.

10 Furthermore, it has been found that the concentration of acid soluble organic matter in the acid, hereinafter termed acid soluble oil, is effective in producing improved results.

Finally, although the conversion is a liquid 15 phase conversion; i. e., both the charge stock and the hydrofluoric acid are in the liquid state, that the pressure under which the reaction proceeds, has an effect upon the quality of the products produced.

20 In general, the present method provides for the treatment of mixtures of hydrocarbons, especially naphthas, with hydrogen fluoride in liquid state in amounts greater than that required to saturate the hydrocarbon charge with 25 hydrogen fluoride and not more than in the ratio of 2 volumes of hydrofluoric acid to 1 volume of hydrocarbon charge stock at temperatures of the order of 270° F. to 470° F. and preferably in the range of 320° F. to 450° F.

It has been found that the hydrofluoric acid 30 should contain at least 4 per cent by weight and not more than about 40 per cent by weight of acid soluble oil and not more than about 10 per cent of water.

35 It has been found that, generally, the hydrocarbon stock at room temperature is saturated with hydrogen fluoride when a concentration of about 0.5 per cent hydrogen fluoride is attained. Consequently, an amount of hydrogen fluoride in 40 excess of about 0.5 per cent by weight of the hydrocarbon charge is in excess of that amount required to saturate the hydrocarbon charge.

Although any mixture of hydrocarbons can be 45 treated, the present method is very readily illustrated by discussion of the treatment of naphthas. Thus, for example, the treatment of naphthas having a boiling range of about 250° to 400° F. and naphthas having a boiling range of about 315° to 400° F. will be used to illustrate the 50 basic principles of the present method of converting hydrocarbons.

As shown in a more or less diagrammatic manner in Fig. I, the fresh hydrocarbon charge from a source not shown is passed by means of line 55 10 through heat exchanger 11 and line 12 to re-

3

actor 13. Liquid hydrogen fluoride or hydrofluoric acid is introduced into reactor 13 by conduit 14 under the pressure required by the pressure in reactor 13. Reactor 13 is of sufficient capacity to provide a residence time sufficient that a conversion of less than 40 per cent to liquid products having a 90 per cent point below the 10 per cent point of the charge stock is obtained at temperatures of 270° F. to 470° F. and at pressures sufficient to maintain the reactants in the liquid state at the reaction temperature.

The reaction mixture comprising reactants, catalyst and reaction products is passed via line 15 to settler 16. In settler 16 the hydrogen fluoride phase is the lower phase and is drawn-off through line 17 by pump 18.

The hydrocarbon products being lighter than the hydrofluoric acid phase form the upper layer in settler 16 and are withdrawn through line 19 pressure reducing valve 20 and line 21 to the main fractionating tower 22 in which the hydrocarbon products, whose 90 per cent point is at least below the 10 per cent point of the charge stock and saturated with hydrogen fluoride, are withdrawn through line 23, heat exchanger 24 and line 25 to the hydrogen fluoride stripper 26. The remaining higher boiling hydrocarbons are withdrawn from fractionating column 22 through line 27 by pump 28 and recycled to the reactor 13 through lines 29 and 12.

In the stripper 26 hydrogen fluoride and light hydrocarbons are taken as overhead and passed through line 30, heat exchanger 31 and line 32 to settler 33 in which the hydrogen fluoride forms the lower liquid phase and the light hydrocarbons the upper liquid phase.

The hydrocarbon phase in settler 33 is returned through line 34 to stripper 26 to serve as reflux while the hydrogen fluoride is withdrawn from settler 33 through line 35 to line 36.

The hydrogen fluoride phase withdrawn from settler 16 through line 17 in part is transferred to the hydrogen fluoride regenerator 31 in which hydrogen fluoride is taken as overhead through line 38 and heat exchanger 39 and with the hydrogen fluoride from settler 33 returned through lines 36 and 14 to the reactor 13.

Returning now to the hydrogen fluoride stripping operation, the overhead from stripper 26 is hydrogen fluoride and light fractions of the desired product. This overhead is withdrawn as described hereinbefore through line 30. The bottoms; i. e., the desired product having a 90 per cent point lower than the 10 per cent point of the charge stock is withdrawn from stripper 26 through line 40 to storage or for further treatment or other use as the situation requires.

The foregoing has been a description of the general operation of the present method. However, certain factors affect the results of the present method of converting hydrocarbons and require discussion. Thus, for example, it has been established that the acid to hydrocarbon; i. e., hydrofluoric acid to charge stock ratio has a marked effect upon the amount of high boiling or tarry material produced. This is aptly illustrated by the curves of Fig. II. The materials treated to illustrate this effect were two naphthas; one having a boiling range of 250°-400° F. and the other having a boiling range of 315°-400° F. The curves of Fig. II establish that as the ratio of hydrogen fluoride to charge stock is increased from about 0.4 to 5.0 volumes of hydrofluoric acid per volume of charge stock the ratio of converted raffinate; i. e., material having a 90

4

per cent point below the 10 per cent point of the charge stock, to organic material soluble in the hydrofluoric acid phase; i. e., tarry material, decreases from 6 to 1 to 1 to 1. In other words, when treating a charge stock at a given temperature and under a pressure sufficient to maintain the reactants in the liquid phase, the ratio of desired products to undesirable products decreases as the ratio of hydrofluoric acid to charge stock decreases. Thus, at a HF:HC ratio of 0.4-0.5 volumes to 1 volume, the volume of the hydrocarbon product was 6 times the volume of the acid soluble oil. In contrast, when 3 volumes of hydrofluoric acid were used per 1 volume of charge, the ratio of desired product to acid soluble oil was 1 to 1. The foregoing can be stated in another manner. When the hydrofluoric acid to charge stock ratio was 0.4-0.5:1 the desired product was about 86 per cent of the charge stock converted and the acid soluble oil about 14 per cent. However, when the hydrofluoric acid to charge stock ratio was 3:1, about 54 per cent of the charge was converted to desired product and about 46 per cent to acid soluble oil.

It is interesting to contrast the results obtained by Ridgway et al. with those obtained in the present method. At an acid to charge stock ratio of 2.95 to 1, 50 per cent of the charge stock 30 was converted to gas and gasoline while 49.7 per cent was converted to tar. At an acid to charge stock ratio of 1.93 to 1 Ridgway et al. obtained 46.9 per cent gas and gasoline and 53.1 per cent was converted to tar. At or about the same acid 35 to charge stock ratios the present method converts 67 and 60 per cent of the charge stock respectively to raffinate and the balance to acid soluble oil. Thus, the results produced by the present method are diametrically opposed to 40 those obtained in the prior art process.

The curves in Fig. III establish that in the treatment of naphthas as the ratio of acid to charge stock is increased from about 0.5 to about 4.6 to 1 (by volume), the ultimate conversion decreases from about 90 per cent to about 55 per cent.

The foregoing leads to the expression of the preferred conditions as those in which the ratio of hydrofluoric acid or hydrogen fluoride to charge stock is not greater than about 2.5 to 1 and not less than an excess of that amount of hydrogen fluoride required to saturate the charge stock therewith.

A further modification of the basic concept is 55 control of the water and soluble oil content of the catalytic hydrofluoric acid. It has been found that improved results are obtained when the acid contains at least 4 per cent by weight of organic material soluble in the acid catalyst and 60 termed herein acid soluble oil. Figs. IV and V illustrate the fact that with fresh hydrofluoric acid about 9.2 per cent of the charge is converted to organic material soluble in the acid; i. e., acid soluble oil although that represents only about 4 65 weight per cent of the acid phase. When that acid is recycled only about 8 weight per cent of the charge is converted to acid soluble oil in the second pass and about 5 weight per cent in the third and subsequent passes, although the total 70 amount of acid soluble oil reaches about 9 weight per cent of the acid phase in the fourth and subsequent passes. In other words, when the hydrofluoric acid contains about 8 to about 10 weight per cent of acid soluble oil, the conversion of charge stock to acid soluble oil is a minimum.

The results produced by the basic method of operation can be still further improved by carrying out the conversion in the liquid phase at a pressure more than at least 150 p. s. i. greater than the vapor pressure of the products of conversion. Thus, for example, when treating a heavy naphtha from a mid-continent crude, it was found that the octane number of the gasoline produced could be raised about 7 numbers by resorting to this variation in operation. These data are presented in tabular form as follows:

Table

Charge stock	—314°—400° F.	Heavy naphtha.
Reaction temperature	—340° F.	
Contact time	—about 7 minutes.	
HF/HC ratio (volume)	0.5:1.	
Vapor pressure of conversion products at reaction temperature	—780 p. s. i.	
Reaction pressure	—1600 p. s. i.	900 p. s. i.
Pressure differential	—820 p. s. i.	120 p. s. i.
Charge stock octane number	—18.0	18.0
Octane number of conversion gasoline	—77.2	70.0
Ultimate yield, vol. per cent of charge	—80	68

It is manifest that not only is the improvement in octane number markedly greater but the ultimate yield of gasoline is about 18 volume per cent greater as a result of operating at a reaction pressure greater than about 150 p. s. i. greater than the vapor pressure of the conversion products.

The residence time for the conversion reaction varies with the temperature and in general is less the higher the temperature within the interval 270° F. to 470° F. The preferred conditions are a reaction temperature of about 300° F. to 450° F., a residence time sufficient to secure not more than about 40 volume per cent conversion to products having a 90 per cent point lower than the 10 per cent point of the charge stock and preferably a residence time sufficient to obtain only about 20 to 30 per cent conversion to products having a 90 per cent point lower than the 10 per cent point of the charge stock. In general, a residence time of not more than 20 minutes and preferably of the order of 2 to 10 minutes dependent upon the reaction temperature is desirable. With the reaction conditions described hereinbefore, satisfactory results will be obtained employing at least sufficient hydrofluoric acid to form a second liquid phase; i. e., an amount in excess of that required to saturate the charge stock with hydrofluoric acid and not more than about 2.5 volumes of hydrofluoric acid per volume of charge stock and preferably about 0.4 volume to about 1.5 volumes of hydrofluoric acid per volume of charge stock. The results described herein can only be obtained when the reactants are in the liquid state. Consequently, the conversion reaction must be carried out at a pressure at least sufficient at the reaction temperature to maintain liquid state conditions and preferably at least 150 pounds per square inch (p. s. i.) higher than the vapor pressure of the effluent from the reactor at the reaction temperature.

While the present conversion method may be carried out with total recycle or without recycle of the hydrofluoric acid, it is preferred to recycle at least 25 per cent of the hydrofluoric acid. 5 Similarly, while 100 per cent hydrofluoric acid may be used and the concentration of hydrogen fluoride in the catalytic acid should be more than 50 per cent with a maximum of 10 per cent of water, it is preferred that the acid catalyst contain not more than 5 per cent of water and at 10 least 4 per cent of soluble organic material herein termed acid soluble oil. Thus, acid catalyst containing not more than 5 per cent water and having 15 a titratable acidity of at least 50 per cent to about 90 per cent hydrogen fluoride gives satisfactory results.

We claim:

1. A method of converting a mixture of normally liquid hydrocarbons into a liquid product having a 90% point below the 10% point of said hydrocarbon mixture which comprises contacting for about 2 to 5 minutes a mixture of normally liquid hydrocarbons with a catalyst consisting essentially of not more than 10% water, about 4 to about 10% hydrogen fluoride-soluble oil and the balance hydrogen fluoride in the ratio of about 0.25 to 2.0 volume of said catalyst per volume of said hydrocarbon mixture at a temperature of about 200° F. to about 470° F. at a pressure at least 150 p. s. i. greater than the vapor pressure of the reaction mixture, separating a hydrocarbon phase from said liquid catalyst, and recovering from said hydrocarbon phase a liquid 30 product having a 90% point below the 10% point of the charged mixture of hydrocarbons in an ultimate yield of at least 75% of said charged mixture.

2. A method of converting a naphtha into a liquid product having a 90% point below the 10% point of said naphtha which comprises contacting for about 2 to 5 minutes a naphtha with a catalyst consisting essentially of not more than about 5% water, about 8 to about 10% hydrogen fluoride-soluble oil and the balance hydrogen fluoride in the ratio of about 0.25 to 2.0 volume of said catalyst per volume of naphtha at a temperature of about 200 to 470° F. at a pressure at least 150 p. s. i. greater than the vapor pressure of the reaction mixture, separating a hydrocarbon phase from said liquid catalyst, and recovering from said hydrocarbon phase a liquid product having a 90% point below the 10% point of said naphtha in an ultimate yield greater than 55 75% of said charged naphtha.

JOE E. PENICK.
